UNITED STATES PATENT OFFICE.

LYCURGUS LINDSAY, OF LOS ANGELES, CALIFORNIA.

CLASSIFIER FOR MILLED PRODUCTS.

Application filed October 6, 1921. Serial No. 505,774.

To all whom it may concern:

Be it known that I, LYCURGUS LINDSAY, a citizen of the United States, residing at Los Angeles, in the county of Los Angeles and State of California, have invented new and useful Improvements in Classifiers for Milled Products, of which the following is a specification.

My invention relates to a classifier for milled products, the principal objects of my invention being to generally improve upon and simplify the construction of the existing forms of similar types of classifiers, to provide an apparatus of the character referred to, that is of relatively simple structure capable of being easily and economically operated, and which will be very effective in separating pulverized or powdered material into different grades or classes.

29 A further object of my invention is to provide a classifier or separator for milled products and pulverized material that has a number of readily adjustable parts, thereby enabling the material that passes through the apparatus to be very accurately separated into different grades or classes.

With the foregoing and other objects in view, my invention consists in certain novel features of construction and arrangements 30 of parts that will be hereinafter more fully described and claimed and illustrated in the accompanying drawings, in which:

Fig. 1 is a side elevational view of a classifier of my improved construction.

25 Fig. 2 is a vertical section taken on a medial line through the body of the classifier.

Fig. 3 is an enlarged detail section taken in a vertical plane at right angles to the plane of Figs. 1 and 2.

40 Fig. 4 is an elevational view looking in the direction indicated by the arrow 4 in Fig. 2.

Referring by numerals to the accompanying drawings which illustrate a practical embodiment of my invention, 10-10 designate side walls, and 11-11 the end walls of a vertically disposed chute or hollow body through which the material to be classified passes, and arranged in the upper end of said chute is a hopper 12 into which the pulverized material to be classified is delivered.

Arranged immediately below and to one side of the discharge opening at the lower end of hopper 12, and extending between the side walls 10, is a material feeding box 13, in which is arranged for rotation, a feed

roller 14, that is provided on its periphery with a series of radially disposed blades 15.

Feed roller 14 may be driven in any suitable manner, preferably by means of a belt 16 that operates around a pulley 17, that is located at the end of the shaft that carries said roller. The side wall of the box 13 over which the material to be separated and classified is discharged by the roller 14, is 65 provided with a vertically adjustable plate 18, that is raised or lowered according to the character of the material that is being separated and classified in the machine.

Formed in the end wall 11 immediately 70 opposite to this adjustable plate, is an opening 19 in which is located a section 20 of glass or like transparent material, and through which the discharge of material over the upper edge of adjustable plate 18 75 may be observed.

Arranged within the chamber in the chute or body of the classifier and to one side of the medial line thereof, is a series of inclined partitions 21, the lower one of which 80 forms a portion of the bottom of the chute, and formed in the end wall 11, immediately above the lower end of each partition is a graded material outlet opening 22, that is normally closed by an outwardly opening 85 gravity gate or door 23, the same being hinged or pivoted to the end wall of the chute immediately above the outlet opening.

Leading from the chamber above the inclined partitions 21 are separate educts or 90 branch pipes 24, the same being connected to a main suction pipe 25, and which latter leads to the intake side of a suitably located suction fan 26. Extending downwardly and away from the upper ends of the inclined partitions 21, are inclined partitions 27, the lower one of which cooperates with the lowermost partitions 21 in forming the bottom for the chute, and the upper inclined partitions terminate in a vertical plane a 100 short distance away from the adjacent end wall 11. The inclined partitions 27 are located in that portion of the chamber within the chute that is below the feed box 13 and the adjustable plate 18.

105 Journalled in the side walls 10 of the chute, and located between the upper end of the inclined partitions 21 and 27, are transversely disposed shafts 28, each of which carries a vane or deflector plate 29. 110 Secured to the outer end of each shaft 28 is a segmental plate 30, in which is formed

an arcuate slot 31 that is concentric with the axis of shaft 28, and seated in the adjacent side wall of the chute is a pin or bolt 32 that passes through said slot 31, and receives the winged nut 33.

The construction just described provides means for retaining the vanes 29 in their adjusted positions. Depending from the feed box 13 and from points between the 10 upper ends of the inclined partitions 21 and 27, are vertically disposed partitions 34, against which the free ends of the vanes 29 are adapted to engage when moved into vertical positions. The partitions 34 thus 15 serve as stops, while also controlling the movements of air within my classifier.

Journalled in the side walls 10, adjacent to the end wall 11, that is provided with the opening 19, are transversely disposed 20 shafts 35, each of which carries a vane 36 and which latter projects inwardly and downwardly toward the adjacent vane 29, to cooperate therewith in providing a regulable opening below the discharge blade 18 25 of the feed box 13.

The outer end of each shaft 35 carries a segmental plate 37 in which is formed an arcuate slot 38, and seated in the adjacent side wall 10, is a pin 39 that passes through 30 said arcuate slot and receives a winged nut 40.

The construction just described provides simple means for adjusting the positions of 35 the vanes 36 and for locking the same after adjustment. Formed in the end wall 11, immediately beneath each vane 36, is an air inlet opening 41, and hinged to the outer face of the end wall directly above each opening, is an adjustable door 42 carrying a section 42 of transparent material such as glass, and which arrangement permits inspection of the angular positions 40 of the vanes 29 and 36, and likewise inspection of the action of the material passing 45 between the ends of said vanes.

Projecting outwardly from the end of each door 41 is a threaded pin 43 that passes the slot in a pivotally mounted link 44, and said threaded pin, receives a winged nut 45, and which latter when tightened, locks the door in open or closed or any desired position.

Extending inwardly from the end wall 11, that is provided with the air inlet openings 41, and downwardly towards the lower ends of partitions 27, are inclined partitions 46, to the lower ends of which 55 are hinged gravity gates 47, the lower portions of which normally lie against the lower ends of partitions 27.

In the operation of my improved classifier, the material to be graded or classified is delivered into hopper 12, from whence 60 said material passes into box 13, and as the feed roller 14 is operated, the material will

be carried downwardly through the bottom of the box and thence upwardly over the upper edge of plate 18.

Doors 42 are opened to admit air to the chamber within the chute and said doors 70 are retained in open position by tightening the various winged nuts 45 that engage the links 44.

As suction fan 26 is operated, a constant suction of air is produced through the inlet 75 openings 41, thence through the chambers between the vanes 29 and 36, thence between the adjacent ends of said vanes, thence through the chambers beneath the inclined partitions 21, and thence through branch 80 pipes 24 to main suction pipe 25.

As the pulverized or powdered material passes downwardly through the chute, the relatively lighter particles of said material 85 will be carried by the air upwardly through the spaces between the vanes 29 and 36, and by the arrangement of the pairs of inclined partitions 21 and 27 directly above each other, the particles of material of different specific gravities will be separated and will 90 finally pass into the lower portions of the chambers immediately above the inclined partitions 21, and said separated or graded material will be discharged from said chambers outwardly through openings 22, past 95 the gates or doors 23.

Obviously the particles of material of least weight will accumulate in the chamber above the uppermost partition 21, the relatively heavier particles of material will 100 accumulate in the chamber above the intermediate partition 21, the third grade, or still heavier particles of material will accumulate in the chamber above the lowermost partition 21, while the heaviest particles of material or those not affected by the suction of air drawn through the chute, will accumulate in the lower portion of the chamber above inclined partition 27, from whence they may be removed through a suitably located outlet that is formed immediately 105 above the lower end of said lower partition 27.

The positions of the doors 42 with respect to the openings 41, controls the amount of air drawn into the classifying chamber at the different elevations, and such provision together with the adjustability of the vanes 29 and 36 is very effective in bringing about 115 an accurate separation or classification of the particles of material of different specific gravities.

The classifier of my improved construction is relatively simple in structure, may be 120 very economically operated, and is very effective in separating and classifying all kinds of pulverized or milled products.

It will be readily understood that minor 125 changes in the size, form and construction of the various parts of my improved classifier 130

fier, may be made and substituted for those herein shown and described, without departing from the spirit of my invention, the scope of which is set forth in the appended 5 claims.

I claim as my invention:

1. In a classifier for milled products, a vertically disposed chute, a series of oppositely arranged inclined partitions within 10 said chute, which partitions divide the space within said chute into a series of chambers, means comprising separate educts and separate air inlets, one of these being adjustable for producing a suction of air through said 15 chambers, and a pair of adjustable vanes located in the upper portion of some of the chambers.
2. In a classifier for milled products, a vertically disposed chute, a series of inverted 20 V-shaped partitions arranged within said chute and dividing the space therein into a series of chambers, means comprising separate educts for producing a suction of air through each chamber, and an adjustable 25 vane arranged above each inverted V shaped partition.
3. In a classifier for milled products, a vertically disposed chute, a series of inverted V-shaped partitions arranged within said 30 chute and dividing the space therein into a series of chambers, means comprising separate educts for producing a suction of air through each chamber, and an adjustable 35 vane projecting into each chamber from one of the walls of the chute.
4. In a classifier for milled products, a vertically disposed chute provided in one of its side walls with a series of adjustable air 40 inlet openings, a series of superimposed inverted V-shaped partitions within said
- chute, which partitions divide the space within said chute into a series of separating chambers, there being an air outlet leading from each chamber, means for producing a suction of air through each chamber, and a 45 pair of adjustable vanes located within some of the chambers.
5. In a classifier for milled products, a vertically disposed chute provided in one of its side walls with a series of adjustable air 50 inlet openings, a series of superimposed inverted V-shaped partitions within said chute, which partitions divide the space within said chute into a series of separating chambers, there being a separate air outlet 55 leading from each chamber, means for producing a suction of air through each chamber, a pair of adjustable vanes located within said chamber, a material feeding box arranged in the upper portion of the chute, 60 said box having an adjustable side wall, means within said box for discharging the material therefrom over said adjustable side wall, toward a regulable opening between a pair of said adjustable vanes. 65
6. In a classifier for milled products, a chute, a hopper in the upper portion of said chute, a feed box which receives material from said hopper, a feed roller for discharging material from said feed box, means for 70 regulating the discharge of material from said feed box, a series of material separating chambers formed in the lower portion of said chute, and a glazed opening opposite said feed box for observing the rate of discharge therefrom to the uppermost of said chambers. 75

In testimony whereof I have signed my name to this specification.

L. LINDSAY.
